UNITED STATES PATENT OFFICE.

MOSES GOODSIDE, OF NEW YORK, N. Y.

COMBINED CORSET AND ABDOMINAL SUPPORTER.

1,090,844.

Specification of Letters Patent. Patented Mar. 24, 1914.

Application filed April 15, 1913. Serial No. 761,273.

To all whom it may concern:

Be it known that I, MOSES GOODSIDE, a citizen of the United States of America, residing at 444 Grand street, New York, in the county and State of New York, have invented certain new and useful Improvements in Combined Corsets and Abdominal Supporters, of which the following is a specification.

10 My invention relates to a combined corset and abdominal supporter, and while its application is more or less general, it is especially designed for wear by females during pregnancy and after child-birth, and 15 after surgical operations on any of the abdominal organs. The device has also proven to be effective in retaining loose kidneys in normal position, giving support to weak spinal cords, and in reducing abnormally 20 large lower abdomens. As the combined corset and supporter tends to produce a graceful figure, and is comfortable in use, it may be employed for street wear as well as for house wear.

25 The principal object of the invention is to provide a combined corset and abdominal supporter of such construction that while tending to maintain the figure in substantially normal form, it will offer 30 yielding support, without discomfort to the wearer, to any parts of the body affected by surgical operations or by conditions existing before or after child-birth.

35 A further object of the invention is to so construct the device that the support offered thereby will be varying in degrees of elasticity, corresponding to the character or nature of the parts requiring support.

40 Other objects and advantages of the invention will be disclosed in the following specification, reference being made to the accompanying drawing, wherein—

45 Figure 1 is an elevational view of my improved corset and supporter; Fig. 2 is a cross sectional view on the line 2—2 of Fig. 1.

50 During pregnancy, and after child-birth, the lower abdomen requires support of a yielding character, in the former case because of the distended condition of the parts and in the latter case because of the relaxation of the abdominal walls. In either case, the bust requires support, but this support may be less yielding than that afforded the 55 lower abdomen. My improved device takes account of these conditions, and the con-

struction is such as to give the desired degree of support to the several organs, provision being made to properly retain the elastic part of the device against excessive 60 yield or give, and care also being taken to offer no material impediment to the free movement of the lower extremities of the wearer.

Referring in detail to the accompanying 65 drawing, it will be noted that, in the main, the combined corset and supporter is formed of a web of suitable material, preferably silk, divided into four parts or members, numbered 10, 11, 12 and 13, joined together 70 or integral with each other.

The web member 10 is inelastic, and is 75 designed as a bust support. It is sufficiently soft and flexible to avoid all discomfort to the wearer, while maintaining the parts which it confines in substantially normal form. The web portion 10 extends from the bust down to approximately the waist line.

Immediately adjacent the web portion 10 80 is the web portion 11 which is designed to encompass the lower abdomen and extends from the waist line into proximity to the pelvic region. The web portion 11 is so formed as to be highly elastic in the direction of its length, thus exerting a yielding compressive force against the parts which it protects, and following with a clinging pressure all the movement of the lower abdomen. The web portion 11 is somewhat 85 narrower than the bust portion 10, the relation in a standard device being approximately eight inches for the latter and approximately six inches for the former. Next to the web portion 11 is the relatively narrow inelastic strip of web or fabric 12, which is designed to be positioned against the extreme lower part of the abdomen. The strip 12 need not be elastic, and its function, in combination with the bust member 10, is 90 to retain the abdominal member 11 against excessive yield or displacement.

The lower edge of the supporter is formed as an elastic strip 13, the normal position 95 of which is slightly below the hips over the top of the legs; the latter being allowed free movement by reason of the elasticity of the strip 13. The strips 12 and 13 are of about the same width each being approximately one and one half inches wide.

100 The combined corset and supporter is usually made in two sections, connected at

the rear by lacing 14 and at the front by hook and eye connections 15. I also preferably provide the vertical, elastic stays 16 to assist in maintaining the device in proper upright form on the body. Extending from near each front and rear edge toward each other are bifurcating lappets 17 which assist in supporting the abdomen, the lappets on each side being suitably connected together, 10 as by buckles 18, by means of which the pressure to be exerted by the device may be regulated by the wearer, and the tension of the elastic portions of the web adjusted to suit the needs of any given occasion. The 15 device may be provided with the usual form of hose supporters 19, depending from the lower front edges thereof.

What I claim is:—

20 A combined corset and abdominal supporter consisting of two like parts, each embodying an integral web consisting of a single continuous upper inelastic member adapted to support the bust of the wearer and extending from the front to the rear of 25 the device in a direction at right angles to its length, a single continuous intermediate

elastic longitudinally yielding member adapted to extend from the waist line to the pelvic region of the wearer and extending from the front to the rear of the device in 30 a direction at right angles to its length, a relatively narrow continuous inelastic member adapted to be positioned against the extreme lower part of the wearer's abdomen and extending from the front to the rear of 35 the device in a direction at right angles to its length, a continuous lowermost elastic strip or member extending to a point below the hips of the wearer, and extending from the front to the rear of the device in 40 a direction at right angles to its length, a bifurcated lappet connected to the front and rear edge of each of the corset parts, said lappets extending toward each other, and means for adjustably connecting the lappets 45 on each of the corset parts to each other.

In testimony whereof I have affixed my signature in presence of two witnesses.

MOSES GOODSIDE.
